UNITED STATES PATENT OFFICE.

GOTTHOLD L. LANGER, OF PORTLAND, OREGON, ASSIGNOR TO J. M. MASTORAS, OF PORTLAND, OREGON.

CANDY-PULLING MACHINE.

1,232,697.

Specification of Letters Patent. Patented July 10, 1917.

Application filed October 9, 1916. Serial No. 124,563.

To all whom it may concern:

Be it known that I, GOTTHOLD L. LANGER, a citizen of the United States, residing in the city of Portland, county of Multnomah, 5 and State of Oregon, have invented certain new and useful Improvements in Candy-Pulling Machines, of which the following is a specification.

My invention relates to candy pulling 10 machines, and more particularly to a machine adapted to automatically pull candy by means of a floating puller which is carried through a course of travel corresponding in form to the figure 8, and around fixed 15 supporting pins arranged concentrically within the two circular portions of said figure 8, whereby the candy is pulled by said floating puller and alternately carried thereby around said fixed supporting pins.

20 So far as I am aware, I am the first to provide in a machine of the character referred to a floating pulling or carrying-member adapted to be carried first around one circular course in one direction, and then 25 around another circular course in the opposite direction, with means for holding and carrying said puller or carrying member, in the manner indicated.

In order that others may understand my 30 invention I have illustrated the preferred form thereof in the accompanying two sheets of drawings, which I will now describe.

Figure 1 is a vertical, sectional view through the preferred embodiment of my invention, taken on the lines 1-1, on Figs. 2 and 3;

Fig. 2 is a horizontal sectional view through the machine on a line corresponding to line 2-2, Fig. 1;

40 Fig. 3 is a vertical cross sectional view of the invention, substantially on the line 3-3, on Fig. 1;

Fig. 4 is a side elevation of the machine with the floating puller or carrier shown 45 in section;

Fig. 5 is an edge or end view thereof, with parts broken away to reduce the size of the figure; and

Fig. 6 is a vertical longitudinal sectional view through the casing with the gears removed to more clearly illustrate the course of travel of the floating puller or carrier member.

Referring now more in detail to the drawings my invention comprises a base 1, upon

which are supported two circular, or drum-like, casings 2-2, joined together at one side, and in open communication with each other, as clearly illustrated in the drawings, said casing being formed together and provided at their upper side with a connecting portion 3. Revolubly mounted in the opposite sides of each of said drums are side disks, or closures, 4-4 and 5-5, held in place by detachable side rims 6-6, and 7-7, 60 said side disks having formed centrally thereof bearing sleeves, or boxes, as 4^a-4^a, and 5^a-5^a, shown clearly in the horizontal sectional view, Fig. 2, said side disks, or members also having formed on their inner 65 faces inwardly projecting annular flanges, as 4^b-4^b and 5^b-5^b, whereby circular passageways are formed between said flanges and the body of the drums, or casings, 2-2, as will be clear from Fig. 6. 70

Mounted in said bearing boxes 4^a-4^a and 5^a-5^a are two shafts, or pins, 8 and 9, which project through the sides of said casing, as will be understood from Figs. 2, 3 and 5. Mounted upon the middle portions of said 75 shafts, or rods, 8 and 9, within the drums, or casings 2-2, are two large gears 10 and 11, having long hubs, as 10^a and 11^a. Said side disks, or members, 4-4 and 5-5, and said gears 10 and 11, and said shafts 8 and 9, 80 are all secured to turn together within said drums, or casings, said gears meshing with each other through the adjacent open sides of the drums, or casings, 2-2, as clearly seen in Fig. 1. The gear teeth of said gears 85 10 and 11, it will be noted, project into the annular passageways formed within the drums, or casings, 2-2, and around the outside of the inwardly projecting flanges 4^b-4^b and 5^b-5^b, on the revolving side members 90 of the casing. 95

Said gears 10 and 11, each has formed at one place in its rims, in place of the teeth, a half round socket, as 11^a, Fig. 1, which when the gears come together with these corresponding sockets in register with each other, as seen in Fig. 1, a round socket is formed between the meeting gears sufficient in size to encircle and carry what I will call a floating puller, or carrier, 12, comprising a rod, or shaft extending through the drum, or casing, 2, and at opposite sides thereof, to a distance corresponding in length to the rods, or shafts, 8-8 and 9-9, said floating carrier 12, being preferably bowed at its oppo- 100

105

110

site ends, as at 12^a—12^a, Fig. 5. The side members, or disks, 4—4 and 5—5, have also formed in their peripheries as at 4^c—4^c and 5^c—5^c, Fig. 4, coöperating sockets adapted to fit around said floating carrier 12, as it passes between the meeting edges of said side disks or members, it being understood that the sockets formed in the gears 10 and 11, and the sockets formed in the side disks, or members, 4—4 and 5—5, come together in register with each other, as seen in Figs. 1, 2 and 4, once in each revolution of said gears and said side members, whereby to carry said floating carrier 12, between said gears 10 and 11, which are in mesh with each other.

In order to more steadily support and guide said floating carrier 12, there is mounted on the hub 10^a, of the gear 10, at opposite sides of the gear 10 and secured thereto, a pair of arms 13—13, shown in side view in Fig. 1, and in section in Fig. 2, said arms being provided at their outer ends with forks 13^a, adapted to fit around said floating carrier 12, as it is carried around said gear 10, within the guide way formed between the flanges 4^b and 5^b and the inside of the drum 2. Pivotaly mounted through the casing, or drum 2, at the lower side of the juncture thereof, on opposite sides of the gears 10 and 11, are pivoted switch levers, as 14, adapted to be moved from one side to the other, by said floating puller, whereby to direct the course of travel of said floating carrier 12, in a manner hereinafter referred to.

Also pivotally mounted in the upper side of the juncture between said drums, or casings 2—2, is another pair of switch levers, as 15, each having two projecting ears, as 15^a—15^a, provided with rollers 15^b—15^b, as shown, whereby said switch levers 15, are moved from one side to the other by said floating carrier 12, as it is carried through the passageway, referred to, within one or the other of said drums, or casings. A spring-pressed plunger 16, is mounted in the connecting web, or box, 3, between said casings, and has a yielding, frictional engagement with a notched lug 17, formed as a part of said switch levers 15. Mounted on the opposite sides of the gear 11, on its hub 11^a, are two arms 18—18, corresponding with the arms 13—13, at the opposite sides of the gear 10, excepting that the outer ends of the arms 18—18, are provided with rounded end portions, as 18^a, projecting slightly beyond the teeth of the gear 11, as will be clear from Figs. 1 and 2. The gear 10, is driven from the gear 11. The gear 11 is driven by a pinion 19, mounted on a shaft 20, having its bearings mounted on the base 1, as at 21, Fig. 4, said gear running through an opening 1^a, in the base 1, as seen in Fig. 1, said pinion 19, being provided on its opposite sides with short arm members 22, provided

with a fork, as 23, corresponding in shape to the forks 13^a, at the outer ends of the arms 13, for the purpose of receiving the floating carrier 12, as it passes between the large gear 11, and said pinion 19. Mounted on the shaft 20, at opposite sides of the pinion 19, are two gears 24—24, adapted to mesh with two gears 25—25, on a common hub 25^a, on a shaft 26, mounted in the bearing boxes 27—27, on the under side of the base 1, said machine being driven by any suitable power applied to said shaft 26. It will be evident that the function of the arms 18—18, having the round heads 18^a—18^a, at opposite sides of the gear 11, is to make a proper mesh with the fork 23, on the pinion 19, when said gear and said pinion come together at these points at a time when the floating carrier 12, is in some other part of its course of travel.

The use and operation of my invention may be briefly described as follows:

As the pins 8 and 9, project at opposite sides of the machine, through the centers of the respective drums, or casings, and the floating pin, or puller member, 12, also projects from the opposite sides of said casing, it will be evident that a batch of candy to be pulled can be laid upon the projecting pins 8, 9 and 12, on either side of the machine, or that two batches of candy to be pulled can be placed upon said pins, one batch on each side of the machine. Assuming that the batch of candy has been stretched across the pins 8 and 9, and the puller member 12, while it is in a position in horizontal alignment with the pins 8 and 9, it will be evident that as the machine is operated through the main driving shaft 26, that the floating puller 12, will move upwardly from its position shown in Figs. 1 and 6, and 105 around the pin 9, as indicated by the arrows, carrying the middle portion of the candy around the pin 9. As the floating puller 12, passes the projecting arm 15^a, of the switch member 15, it will move said switch member over to the right of the center line of the machine, whereupon as said puller member comes around to its middle, or starting position, it will be directed to the left, around the pin 8, pulling and stretching the candy carried thereby at its outer ends around the outer ends of the pin 8. As said floating puller 12, starts around to the left with the large gear 10, it will engage the short arm 15^a, of the switch 15, and move 110 it over to the left again, in the position shown in full lines, whereupon as said floating puller comes again to its middle or starting position it will be directed again around the pin 9, with the large gear 11. Thus said floating puller is alternately carried around the pin 9, by the socket 11^a, in the large gear 11, and around the pin 8, by the forks 13^a, in the ends of the arms 13, which are secured to the large gear 10. This 130

movement laps the candy around the pin 9, then stretches it and laps it around the pin 8, and then stretching it again laps it around the pin 9, pulling and stretching the candy as the floating puller 12, is carried through its course of travel, corresponding to the figure 8.

I am aware that changes can be made in my invention as here illustrated, without departing from the spirit thereof, and I do not, therefore, limit my invention to the particular embodiment thereof here shown and described, except as I may be limited by the hereto appended claims.

15 I claim:

1. In a candy pulling machine, in combination, a supporting structure, supporting pins projecting therefrom at a space apart, a floating pin, or puller, supported in and 20 projecting from said structure, and means for carrying said floating pin, or puller, alternately around said supporting pins, said supporting and floating pins having their supporting attachments in substantially 25 the same plane and all projecting therefrom in the same direction.

2. In a candy pulling machine, in combination, a supporting structure, supporting pins projecting therefrom in parallel relationship 30 with each other and at a space apart, a floating pin, or puller, supported in and projecting from said structure, and means for carrying said floating pin, or puller, alternately around said supporting pins in substantially parallel relationship 35 therewith, said supporting and floating pins having their supporting attachments in substantially the same plane and all projecting therefrom in the same direction.

40 3. In a candy pulling machine, in combination, a supporting structure comprising two drum-like casings joined together edge-wise, a supporting pin supported centrally in each of said casings and projecting 45 axially from the side thereof, a floating pin, or puller, movably supported in said casings and projecting from the side thereof in the same direction and in substantial parallel relationship with said supporting pins, and 50 means within said casings for carrying said floating pin, or puller, first around one of said supporting pins and then around the other of said supporting pins in an opposite direction, whereby said floating pin, or puller, moves through a course of travel 55 corresponding to a figure 8 around said supporting pins.

4. A candy pulling machine comprising in combination a supporting structure, a cas-

ing, two large gears revolvably supported in 60 said structure, in mesh with each other, a supporting pin projecting axially from each of said gears through the side of said supporting structure, a floating pin, or puller, movably supported in said structure, and 65 means on said gears for carrying said floating pin, or puller, first by one gear around its supporting pin and then by said other gear in an opposite direction around its supporting pin, whereby said projecting 70 floating pin, or puller, is carried alternately, in opposite directions, around said projecting supporting pins, substantially as described.

5. In a machine of the character referred 75 to, in combination, a casing, a pair of supporting pins with means for supporting the same at a space apart in substantial parallel relationship with each other, a floating pin, or puller, means for supporting the same in 80 substantial parallel relationship with said supporting pins and for carrying it first around one of said supporting pins and then around the other of said supporting pins, in opposite directions, said supporting pins 85 and said floating pin having their middle portions supported between the sides of said casing with their opposite ends projecting through the opposite sides thereof and means for automatically changing the course 90 of travel of said floating pin, or puller, whereby it is directed first around one of said supporting pins and then around the other of said supporting pins in an opposite direction, substantially as described. 95

6. In a machine of the character referred 100 to, in combination, a casing, two supporting members supported therein at a space apart, a floating puller member movably supported, means for carrying the same bodily through 105 two circular courses of travel, first around one of said supporting members at a space therefrom, and then around the other of said supporting members at a space therefrom, and in an opposite direction, and a switch 110 member movably interposed at the inner section of said courses of travel, and means for automatically and alternately moving the same from one side to the other, whereby to alternately change the direction of travel of 115 said floating member, substantially as described.

Signed at Portland, Multnomah county, Oregon, this 29th day of September, 1916.

GOTTHOLD L. LANGER.

In presence of—

I. M. GRIFFIN,

J. C. STRENG.
